UNITED STATES PATENT OFFICE.

JORDAN L. MOTT, JR., OF NEW YORK, N. Y.

BIDET ATTACHMENT FOR WATER-CLOSETS.

SPECIFICATION forming part of Letters Patent No. 312,373, dated February 17, 1885.

Application filed May 19, 1884 (No modl.)

To all whom it may concern:

Be it known that I, JORDAN L. MOTT, Jr., of the city and State of New York, have invented an Improvement in Bidet Attachments 5 for Water-Closets, of which the following is a specification.

Water-closets have heretofore been provided with a curved pipe that when not in use occupies a nearly horizontal position, and can 10 be swung down and the water turned on so as to direct a jet of water against the person while seated upon the closet. These bidet attachments are liable to leak, and usually require a special character of bowl or closet to 15 which to be applied.

My bidet attachment is made so as to be applied to almost any of the closets in general use, and the same cannot be swung up to its 20 normal position out of use until the water is shut off and the stem of the cock is used for swinging the jet-pipe up or down, and also for turning on the water to any desired extent.

In the drawings, Figure 1 is a plan view of the bidet attachment with part of the slotted 25 cup-plate removed. Fig. 2 is a section longitudinally through the plug. Fig. 3 is a cross-section in larger size at the line *x x*, Fig. 2; and Fig. 4 is an elevation, partly in section, at the line *y y*, Fig. 1.

30 The frame A is usually of cast-iron, adapted to being placed beneath the wood-work B of the closet at one side of the seat. This frame has inverted legs and a flange to rest against the under side of the wood-work, and the 35 screws *c c* are employed to secure the same in place. Usually these screws will pass through the rim of the slotted lever-cup D, that is let into the surface of the wood-work, through such wood-work, and into the flanges, as shown.

40 The two inverted legs *e e* form guides that receive between them the square or head portion *e'* of the barrel *f*, and *g* is a cylinder screwed upon the end of this barrel *f*, and having upon its exterior surface a lock or 45 clamping-nut, *h*, which is screwed up against the legs *e e*, to clamp the head portion firmly against the grooved portions of such legs, which form the guides, and thereby hold the barrel *f* firmly in place at whatever position it may 50 be adjusted to. The water-pipe and coupling-tube *l* are attached to the end of this cylinder *g*. Within the barrel *f* is the tapering plug

k, that is drawn into its place by the nut *i*, with a washer applied at the smaller end of such plug, and this plug is hollow, and there 55 are two cross-holes, *o o*, the plug being solid between them, and in the barrel there are two longitudinal recesses at 2 2 for short distances, that correspond with the ends of the cross-holes when the bidet-pipe is turned into position for use, Figs. 2 and 3; hence the water will pass along through this plug when in this position, but it will be shut off when the plug *k* is turned into any other position. The end of the barrel *f* is partially removed, and a 60 pin, *p*, inserted into the plug *k*, so as to form a stop that limits the movement in turning the plug to swing the bidet-pipe into position for use, and in turning it back to the place occupied when not in use. The plug 65 *k* is extended along and formed as a second barrel, *r*, in which is the plug *s*, with a hole through it, so as to form a cock, and from this plug *s* the crank-lever handle *s'* extends up through the slot in the cup *D*, and at the 70 end of the plug *k*, beyond the barrel *r*, is the bidet-pipe *t*, which extends out axially with the plug *k* a sufficient distance to pass over the top of the ordinary water-closet basin. It 75 is then bent off as an arc of a circle, and terminates as a jet or sprinkler, *v*. The shape and curvature of the bidet-pipe is such that when it is turned down in place for use the jet *v* will be nearly central within the water-closet, and about six inches below the seat, so that the water issuing therefrom will be directed against the person for washing the same, and when turned up out of the way the bidet-pipe will 80 lie under the flange of the closet-bowl, or adjacent thereto, so as not to interfere with the 85 ordinary use of the closet.

It will now be understood that when the bidet attachment is not in use the handle *s'* is nearly horizontal, as shown by full lines in Figs. 1 and 4, with the knob or end within the 90 cup *D*, and the cock *s* is closed, and the water is also shut off at the plug *k*. When the lever-handle *s'* is raised to the position shown by dotted lines at *a'*, Fig. 4, the plug *k* is turned, the bidet-pipe is swung down into position for use, 95 and the water-ways of the plug *k* brought into line with the recesses at 2 2 in the barrel *f*, so that the water is turned on at the plug *k*, but it cannot run through the bidet-pipe, because 100

the cock s is still closed. Upon turning the lever-crank handle s' to the position shown by full lines in Fig. 2, and dotted lines at a^2 , Fig. 4, the water is free to pass through the cock s , and the cock s can be opened or closed and the flow of water regulated at will; but the bidet-pipe cannot be swung aside out of the way until the cock s has first been closed, because the crank of the lever-handle s' has to be brought into line with the slot in the cup-plate D before said crank-lever handle can be turned down into such cup. By this construction the water cannot be turned on or accidentally remain running unless the bidet-pipe is in proper position within the closet. There is very little risk of leakage, because the plugs are the same as those of ordinary cocks; but to prevent injury by leakage at the cocks it is preferable to make the lower part of the frame A dishing to the pipe w , which is connected to the closet or waste pipe, so that leakage may be conveyed away.

I claim as my invention—

1. The combination, with the water-supply pipe and bidet-pipe, of a swivel-coupling and turning-cock, and a crank-lever handle to the plug of the cock, whereby the cock and bidet-pipe can be turned into place for use without turning on the water, and the cock can be opened or closed independently of the movement of the bidet-pipe, and by one handle, substantially as set forth.
2. The combination, with the water-pipe, swivel-coupling, turning-cock, and the bidet-

pipe, of a crank-lever handle to the plug of the cock, and a slotted cup, into which slot the lever-handle can be swung only when the water has been shut off, substantially as set forth.

3. The combination, with the water-pipe and the bidet-pipe, of two supply-cocks, one of which forms the swivel upon which the bidet-pipe is swung, the other being a turning-cock, and a lever-handle connected to the plug of the other cock, by means of which handle the bidet-pipe is moved and the water turned on and off by independent movements of the lever-handle, substantially as set forth.

4. The frame A , slotted cup D , and screws connecting the same, in combination with the plug k , having an operating stem or handle, barrel f , and head, the barrel g , and clamping-nut, the water-supply pipe, and the bidet-pipe extending in line with the plug k and then bent into the arc of a circle, substantially as set forth.

5. The combination, with the bidet-pipe, of the tubular plug k , having an operating stem or handle having two cross-holes, the barrel g , having recesses, and the stop-pin and stops on the plug and barrel, respectively, substantially as specified.

Signed by me this 10th day of May, A. D. 1884.

JORDAN L. MOTT, JR.
